UNITED STATES PATENT OFFICE.

ALLISON E. LABEREE AND ARTHUR B. HAWKS, OF OLYMPIA, WASHINGTON.

DESIGN FOR AN EGG-BEATING BOWL.

49,902.

Specification for Design.

Patented Nov. 14, 1916.

Application filed July 14, 1916. Serial No. 109,393. Term of patent 14 years.

To all whom it may concern:

Be it known that we, **ALLISON E. LABEREE** and **ARTHUR B. HAWKS**, citizens of the United States, residing at Olympia, in the county of Thurston and State of Washington, have invented a new, original, and ornamental Design for Egg-Beating Bowls, of which the following is a specification, reference being had to the accompanying drawing, forming a part thereof.

The figure is a perspective view of an egg beating bowl, showing our new design.

We claim:

The ornamental design for an egg beating bowl, as shown.

ALLISON E. LABEREE.
ARTHUR B. HAWKS.

Witnesses:

J. T. OTIS,
SYLVINA MILLER.
